(57) **CLAIM**

The ornamental design for a children's coordination mirror, as shown and described.

DESCRIPTION

FIG. 1 is a front perspective view of a first embodiment of a children's coordination mirror, showing my new design; FIG. 2 is a rear perspective view thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof;

FIG. 9 is a front perspective view of a second embodiment of the children's coordination mirror; and, FIG. 10 is a rear perspective view thereof.

The broken lines in the drawings illustrate the portions of the children's coordination mirror, which form no part of the claimed design.
